HOIST CONTROL MECHANISM

Burton S. Aikman, Wilkinsburg, Pa., assignor to
The Westinghouse Air Brake Company, Wil-
merding, Pa., a corporation of Pennsylvania

Application July 31, 1941, Serial No. 404,859

8 Claims. (Cl. 60—51)

This invention relates to hoist or elevator control systems and more particularly to the hydro-pneumatic type in which a liquid such as oil is displaced by compressed air for actuating a piston or the like to elevate a body.

One object of the invention is the provision of an improved system of this type.

Another object of the invention is the provision of a system of this type in which the liquid pressure actuated hoisting piston or element can not drop in case of failure of the supply of compressed air on the hoisting liquid as during or after the completion of a hoisting operation.

Another object of the invention is the provision of an improved hoist control system of the hydro-pneumatic type embodying means for reclaiming the compressed air used to effect a hoisting operation so as to accelerate the restoration of the compressed air supply in preparation for a subsequent hoisting operation and to also minimize the amount of power consumed in maintaining the required amount of compressed air for operating the system.

Other objects and advantages will be apparent from the following more detailed description of the invention.

Description

In the accompanying drawing the single figure is a diagrammatic view, mainly in section, of the improved hoist or elevator control system.

In the drawing the reference numeral 1 indicates a compressed air storage reservoir which, when the system is in use, is adapted to be maintained charged with air at a pressure between chosen limits such as from one hundred and fifty-five to one hundred and seventy-five pounds per square inch, and from which compressed air is adapted to be drawn or used for controlling hoisting or elevating operations, in a manner to be described.

The reference numeral 2 indicates an air compressor which for the purpose of illustration is preferably of the compound type comprising a low pressure piston 3 and a high pressure piston 4. These pistons are connected for operation to a crank shaft 5 which is suitably supported in end bearings 6, only one of which is shown. The crank shaft 5 extends through the one end bearing 6 and on its outer end is provided with a pulley 7 which by means of a belt 8 is operatively connected to a drive shaft 9 of an electric motor 10. Outboard of the crank shaft bearing 6 the compressor casing carries an oil seal 11 which contacts the periphery of the crank shaft extend-

ing therethrough. This seal is of the pressure type adapted to prevent leakage of lubricating oil from the crank case 12 along the crank shaft 5 when the pressure in the crank case is above that of the atmosphere.

In operation the low pressure piston 3 is adapted to draw air from an intake pipe 13 and to compress same into one end of an intercooler 14, the opposite end of which is connected to the intake for the high pressure piston 4. The high pressure piston is then adapted to compress the air taken from the intercooler and to discharge same through a discharge pipe 15 into reservoir 1. In order to substantially equalize the forces on the two pistons while operating, the displacement of the low pressure piston 3 is preferably such as to provide a pressure in the intercooler 14 of for instance substantially forty pounds per square inch when the intake pipe 13 is open to the atmosphere providing for the charging of the low pressure cylinder at substantially atmospheric pressure. The high pressure piston is adapted to increase the pressure from that in the intercooler to the degree desired in the reservoir 1, such as from one hundred and fifty-five to one hundred and seventy-five pounds per square inch above mentioned.

The electric motor 10 is adapted to be controlled by an electric governor 20 of any desired type which will respond to the pressure in the reservoir 1. This governor may be adjusted to open the circuit through the motor 10 for stopping the compressor 2 when the pressure in the reservoir 1 is increased to the desired degree such as one hundred and seventy-five pounds above mentioned, and to close said circuit when the pressure in the reservoir becomes reduced to a certain lower degree such as one hundred and fifty-five pounds, so as to cause the motor 10 to operate the compressor 2 for restoring the pressure in said reservoir.

The pressure governor is preferably associated with a cutout device 21 which under a certain condition to be later described is adapted to render said governor non-responsive to the pressure of the compressed air in the reservoir 1.

The cutout device 21 comprises a casing having a passage 22 connecting the governor to a chamber 23 which normally is open past a valve 24 to a passage 25 in constant communication with the reservoir 1. With the valve 24 open as shown, the governor 20 is therefore connected to the reservoir 1 so as to operate in the normal manner in response to pressure variations in said reservoir.

The valve 24 is provided on one end of a stem 26 on the opposite end of which is a valve 27 arranged to control communication between chamber 23 and a chamber 28 which is open to the atmosphere through a passage 29. A control spring 30 in chamber 23 acts on an annular collar 31 provided on the stem 26 for urging the valve 27 closed and for opening the valve 24. A pin 32 projects from the valve 27 into chamber 28 in axial alignment with a plunger 33. The plunger 33 has on its outer end a follower 34 contacting one side of a flexible diaphragm 35 which is clamped around its edge in the casing. At the opposite side of the diaphragm is a pressure chamber 36 which is connected to the compressor intake pipe 13 and which under a condition to be later described is adapted to be charged with fluid under pressure. A chosen relatively low pressure, in chamber 36, such as two pounds above atmospheric pressure, is adapted to overcome control spring 30 and deflect diaphragm 35 in the direction of the left-hand for thereby unseating the valve 27 and for seating the valve 24. When this condition occurs, control passage 22 for the governor 20 will be opened to the atmosphere through chamber 23 past the valve 27 and thence through chamber 28 and port 29 for thereby reducing the control pressure on the governor to a degree such as to cause said governor to operate to close the electric circuit through the motor 10.

The reference numeral 40 indicates an oil reservoir containing a body of oil. Mounted on the top of the reservoir 40 is a manual control valve device 41 which comprises a vertically extending control handle 42 pivoted at its lower end on a shaft 43. At one side of the handle 42 is a stand pipe 44 extending through the interior of the reservoir 40 to near the bottom thereof. Connected to the device 41 outside of the reservoir 40 is a liquid supply pipe 45 adapted to be connected to the elevating piston or plunger (not shown) of the mechanism for conveying liquid under pressure thereto to effect a hoisting operation. The device 41 contains a check valve 46 so arranged as to provide for flow of liquid in the direction from pipe 44 to pipe 45 but to automatically prevent flow in the opposite direction. A spring 47 acting on check valve 46 is provided for urging same to its closed position shown.

A pin 48 projects from the end of check valve 46 opposite that engaged by spring 47. This pin is aligned with a longitudinally movable plunger 49 which is disposed in a suitable bore in the device and has an oil tight fit with the side wall thereof. The outer end of plunger 49 is aligned for movement by an intermediate portion of a lever 50 which is fulcrumed at one end on a pin 51. The opposite end of lever 50 is arranged to be engaged by one side of handle 42 upon rocking said handle in a clockwise direction from the normal position shown to thereby actuate said lever and plunger 49 to unseat the check valve 46. With the handle 42 in its normal position as shown, and also counterclockwise movement of said handle from said normal position, the valve 46 is adapted to be maintained seated by spring 47.

Above the body of oil in reservoir 40 is a chamber 55 to which compressed air is adapted to be supplied from the reservoir 1 for displacing oil from said reservoir into pipe 45 to effect a hoisting operation and from which compressed air is adapted to be released to permit oil to be

released from the pipe 45 for lowering the hoisting element. The supply of compressed air to and its release from chamber 55 is adapted to be controlled by a valve mechanism 56 which forms a part of the manual control valve means 41 but which is located on the side of handle 42 opposite the check valve 46.

The valve mechanism 56 comprises a casing having a chamber 57 which is connected by pipe 58 to the compressed air reservoir 1 and thus in use is constantly supplied with compressed air. In the casing a valve 59 is arranged to control communication between chamber 57 and a chamber 60 which is open to chamber 55 above the oil in reservoir 40. The valve 59 is connected to a piston 61 which is subject on one face to the pressure of compressed air in chamber 57. At the opposite side of piston 61 is a chamber 62 containing a bias spring 63 acting on the piston for urging the valve 59 to its closed position. Above the piston 61 is a chamber 65 which is in constant communication with chamber 62 through a passage 66. A valve 67 contained in the chamber 65 has a fluted stem 68 extending through a suitable bore in the casing in alignment with the left-hand side of handle 42. Projecting from the opposite side of valve 67 is a pin having on its end a tapered valve 69 adapted to cooperate with an aligned seat in the casing. A bias spring 70 in chamber 65 acts on the valve 67 for seating same and for unseating the valve 69. This condition of these valves is adapted to be maintained with the handle 42 in the vertical position shown or upon movement from this position in a clockwise direction. Movement of the handle 42 from its vertical position in a counterclockwise direction is however adapted to unseat the valve 67 and seat the valve 69.

The valve 59 is provided for supplying compressed air from the reservoir 1 to chamber 55 in the oil reservoir 40 and for cutting off such supply. Coaxially aligned with this valve is an oppositely seating valve 75 which is provided for controlling the release of compressed air from chamber 55. The valve 75 is contained in chamber 76 and has a fluted stem 77 which is slidably mounted in a bore connecting said chamber to the chamber 60. The two valves 59 and 75 are connected together for movement in unison by a pin 78 connecting the stems of the two valves.

The reference numeral 83 indicates a pressure reducing valve device which has a chamber 82 to which the inlet pipe 13 of the compressor is connected. An air cleaner or strainer 80 is connected to the pressure reducing valve device 83 to provide for flow of air from the atmosphere to the chamber 82 and then through the inlet pipe 13 to the air compressor 2 during its normal operation. This flow of air through the strainer device 80 to chamber 82 occurs through a chamber 84 containing a disk type check valve 85 adapted to open under such flow but to close communication from chamber 82 to the atmosphere through the air strainer 80 at other times.

Chamber 76 in the supply and release valve mechanism 56 is connected by a pipe 81 to a chamber 88 in the reducing valve device 83. A valve 89 is contained in the chamber 88 and has a fluted stem 90 extending through a bore connecting said chamber to the chamber 82. A pin 91 slidably mounted in a suitable bore is connected at one end to the lower end of the valve stem 90 and projects into a chamber 92 wherein

it is provided with an annular enlargement 93 contacting one side of a flexible diaphragm 94. A plunger 95 engages the opposite face of the diaphragm 94 and is acted upon by a spring 96 which urges the diaphragm in the direction for unseating the valve 89. The chamber 92 is connected to chamber 82 by a passage 97, while chamber 98 containing spring 96 is in constant communication with the atmosphere through a breather port 99. The pressure of spring 96 on the diaphragm 94 is such as to require a chosen degree of fluid pressure in chamber 92, such for example as forty pounds per square inch, for deflecting said diaphragm against the spring to thereby permit seating of the valve 89. When any lesser degree of fluid pressure is effective in chamber 92 and thereby in chamber 82 the spring 96 is adapted to unseat the valve 89.

Operation

Let it be assumed that the reservoir 40 contains an adequate amount of oil for controlling hoisting or elevating operations and that oil from the hoist supply pipe 45 has been released to said reservoir, in a manner to be hereinafter described, to a degree which provides for lowering of the hoisting element or piston to its normal position. Let it also be assumed that the handle 42 is in the vertical position shown in which it will be normally carried and that the whole system including the air supply reservoir 1 is void of compressed air. Let it further be assumed that the compressor 2 and motor 10 are not operating, due for instance to a line switch 100 in the circuit of said motor being open.

To condition the system for operation, the line switch 100 is closed and since the pressure in reservoir 1 is below the cutting out point of the pressure governor 20, said governor will close the circuit to the motor 10 and cause the compressor 2 to operate to draw air from the inlet pipe 13 and to compress same into the storage reservoir 1. Under this condition the drawing of air from pipe 13 will create a sufficient reduction in pressure in chamber 82 in the pressure reducing valve device 83 to provide for atmospheric pressure acting through the strainer device 80 on the lower face of the check valve 85 to lift said check valve whereupon the compressor 2 will draw air directly from the atmosphere for compressing into the reservoir 1. The check valve 85 is preferably a relatively light weight disk so as to offer substantially no interference with the free flow of air from the atmosphere to the compressor, as just mentioned.

During initial charging of the reservoir 1 diaphragm chamber 36 in the cut-off device 21 will be at substantially atmospheric pressure so that spring 30 will be effective to maintain valve 27 seated and valve 24 unseated, thereby subjecting the electric governor 20 to control by the compressed air supplied to the reservoir 1.

The compressor 2 will thus operate to pump air into the reservoir 1 until the pressure in said reservoir is increased to the cutting out point of the governor 20, which may be adjusted to operate to open the circuit through motor 10 when the pressure in the reservoir is increased to the one hundred and seventy-five pounds per square inch above mentioned. When this pressure is attained, the motor 10 and therefore the compressor 2 will be stopped.

As air is compressed into the reservoir 1 it flows through pipe 58 to chamber 57 in the manual control device 41 and from said chamber past

the unseated valve 69 to chamber 62 at the opposite face of the piston 61. The pressure of the air acting on opposite faces of the piston 61 thus being the same permits the bias spring 63 to hold valve 59 seated. With valve 59 seated, the valve 75 is unseated so that chamber 55 above the oil in reservoir 40 will be opened past the valves 75 and 89 to chamber 82 which at this time is substantially at atmospheric pressure. The valve 89 will be unseated at this time by spring 96 due to the fact that substantially atmospheric pressure will be acting in chamber 92 above the flexible diaphragm 94. The system is now in condition for operation.

Let it now be assumed that it is desired to effect a raising or elevating operation. To accomplish this, the operator moves the handle 42 from the normal vertical position shown in a counter-clockwise direction to unseat the valve 67 and seat the valve 69. When the valve 67 is unseated, the compressed air in chamber 62 is vented to the atmosphere past said valve along the fluted stem 68. The pressure of the air in chamber 57 at the opposite side of piston 61 then moves said piston toward the right-hand against spring 63 and such movement unseats the valve 59 and seats the valve 75. Compressed air supplied from the storage reservoir 1 to chamber 57 then flows past the valve 59 to chamber 60 and thence to chamber 55 above the oil in reservoir 40.

The compressed air thus supplied to chamber 55 and acting on the top of the body of oil in reservoir 40 is adapted to force said oil out through the stand pipe 44 to the check valve 46 and unseat same against the light bias spring 47 so as to then flow to the pipe 45 leading to the hoisting means for actuating same to effect an elevating operation.

The amount of oil thus displaced into the hoist pipe 45 will vary according to the height to which it is desired to elevate the body being raised, while the degree of air pressure required in chamber 55 for displacing the liquid will vary in accordance with the amount of oil it is desired to displace as well as the weight of the body being elevated. The pressure required in chamber 55 above the oil in reservoir 40 may therefore be equal to the equalization with the pressure in the supply reservoir 1 or of any lesser degree. If such equalization is desired, the handle 42 will be held in its left-hand position until such occurs and will then be relieved of manual force. However, if a lesser degree of air pressure is desired in chamber 55, then the handle 42 will be held in its left-hand position only until such desired pressure is attained and it will then be relieved of manual pressure. Whenever handle 42 is thus released, spring 70 will act to seat the valve 67 and unseat the valve 69 and in so doing will return the handle 42 to its normal vertical position whereupon compressed air will flow from chamber 57 to chamber 62 and thus equalize on the opposite faces of the piston 61. Spring 63 will then operate the piston 61 to seat the valve 59 for closing communication between the supply reservoir 1 and the oil reservoir 40. It will thus be apparent that any desired degree of displacement of oil from the reservoir 40 may be attained and under any desired actuating pressure of compressed air.

It will be noted that as long as there is flow of oil into the hoist supply pipe 45 such flow will hold the check valve 46 open but as soon as the flow ceases, the check valve will be closed by spring 47 to thereby isolate the hoist supply pipe 45 from

any part of the system in which there is compressed air. In case of failure of any part of the system in which compressed air is effective or in case of failure of the supply of compressed air for any reason, the check valve 46 will therefore automatically operate to prevent back flow of hoisting liquid from the hoist supply pipe 45 to the reservoir 40. Thus any such failure can not result in an undesired and possibly disastrous dropping of the elevated load or body.

When compressed air is drawn from the supply reservoir 1 for displacing oil from reservoir 40, the pressure of the air in the supply reservoir will become reduced and if this reduction is below the cutting-in adjustment of the electric governor 20, said governor will operate to close the circuit through the electric motor 10 and cause the compressor 2 to operate to recharge said reservoir. The compressor may be thus caused to operate to recharge the reservoir while the handle 42 is being held in the left-hand or hoisting position and such operation may or may not terminate before it is desired to lower the body which was elevated. Moreover, if the amount of compressed air taken from the reservoir 1 is not sufficient to reduce the pressure therein to that required for causing the governor 20 to start the compressor, the reservoir 1 will not be recharged with handle 42 in the left hand hoisting position, as will be apparent.

Whenever the handle 42 is returned from its left hand raising position to its normal vertical position, the valve 59 is seated as above described so as to close communication between the supply reservoir 1 and chamber 55, and at the same time the valve 75 is unseated so as to connect the chamber 55 to chamber 76. The compressed air previously supplied to chamber 55 for effecting a hoisting operation will then flow to chamber 76 and thence through pipe 87 to chamber 88 in the reducing valve device 83. Under this condition the check valve 46 will act to bottle the liquid in pipe 45 so as to maintain the body previously elevated in its raised position.

When valve 75 is unseated to connect chamber 55 to the reducing valve device, the valve 89 therein will be unseated by spring 96, due to the fact that the pressure in chambers 82 and 92 will at this instant be substantially equal to that of the atmosphere. The compressed air supplied from chamber 55 to chamber 88 will therefore flow past the valve 89 into chamber 82 and thence through the compressor intake pipe 13 to diaphragm chamber 36 in the governor cut-out device 21 and to the intake of compressor 2. The pressure of the compressed air thus obtained in chamber 82 of the reducing valve device 83 will seat the check valve 85 to prevent loss thereof through the strainer device 80, and will also equalize through port 97 into chamber 92 on the upper face of diaphragm 94 and when increased therein to a degree sufficient to overcome the pressure of spring 96 will deflect said diaphragm downwardly against said spring so as to permit movement of the valve 89 in the direction of its seat and thus prevent the pressure obtained in chamber 82 from increasing above that determined by spring 96.

When a relatively light degree of pressure, such as for instance two pounds per square inch, is attained, as above described, in diaphragm chamber 36 of the governor cutout device 21, the diaphragm 35 will be deflected in the direction of the left-hand against the pressure of spring 30. This movement will shift the valve 27 away from its seat and seat the valve 24, with the result that

the governor control passage 22 will be opened to the atmosphere through chamber 23, past the valve 27 and thence through chamber 28 and vent port 29. The control pressure for the electric governor 20 will thus be reduced to substantially that of the atmosphere and as a result said governor will operate to close, if not already closed, the circuit through the motor 10 to thereby cause said motor to operate the compressor 2 to take air out of the intake pipe 13 and to compress same through the discharge pipe 15 into the reservoir 1.

The compressed air thus taken from the intake pipe 13 and chamber 82 in the reducing valve device 83 will tend to reduce the pressure acting in chamber 92 above the diaphragm 94, as a result of which the control spring 96 will unseat the valve 89 to provide such flow of compressed air from chamber 55 into chamber 82 as to maintain a substantial equilibrium between the pressure of spring 96 acting on one side of the diaphragm 94 and that of the compressed air in chamber 92 acting on the opposite side of the diaphragm. The spring 96 and diaphragm 94 are so related that the maximum pressure obtainable in chamber 82 and at the inlet of the compressor under this condition will not exceed a desired degree such as forty pounds regardless of the pressure acting in chamber 55 of the oil reservoir 40, which subsequent to equalization with the pressure of air in the reservoir 1 during a hoisting operation may be as great as for instance one hundred and fifteen pounds.

There are several important reasons for employing the reducing valve device 83 to limit the pressure obtained in the inlet pipe 13 and thereby at the inlet to the compressor 2 to a certain relatively low degree as compared to that which may exist in chamber 55 of the oil reservoir 40. Certain of these reasons will now be discussed.

It will be noted that the inlet pipe 13 to the compressor is connected to the crank case 12 thereof so that whatever pressure is acting in said pipe will also be acting on the low pressure faces of the compressor pistons 3 and 4 in opposition to the pressure of the air being compressed and acting on the upper faces of the pistons during operation of the compressor. The object of this is to minimize the loads on the various bearings and other parts of the compressor particularly when the compressor is recompressing air from chamber 55 above the oil in oil reservoir 40 back into the supply reservoir 1 at which time the pressure in the inlet pipe 13 will be considerably above that of the atmosphere.

When the crank case 12 is charged with air at a pressure exceeding that of the atmosphere as above mentioned this pressure will tend to force oil from the crank case out along the crank shaft and through the pressure seal 11. This seal will efficiently prevent such loss of oil from the crank case only against a certain degree of pressure therein and another reason for using the reducing valve device 83 is therefore to prevent obtaining a pressure in the crank case above said certain degree so as to ensure that the seal 11 will function efficiently.

The reducing valve device 83 is of particular importance when the compressor is of the compound type shown, in order to cause both the high and low pressure pistons 4 and 3 to operate as intended and to avoid excessive loading of the low pressure piston, as will now be described.

Let it be assumed that in effecting a hoisting operation the pressure of the air in reservoir 1 becomes equalized with that in chamber 55 in the oil reservoir 40, at for instance one hundred and

fifteen pounds. If the reducing valve device 83 were not employed, then when the handle 42 were returned to its vertical position shown this one hundred and fifteen pound pressure in chamber 55 would become effective at the intake to the compressor 2 and thus at the pressure side of the low pressure piston 3 upon its intake stroke. The low pressure piston 3 on its compression stroke would then increase the pressure of the air above the piston to a degree above that in the supply reservoir 1 and this air would therefore merely be forced through the inlet and outlet valves for the high pressure piston 4 directly to said reservoir. The low pressure piston 3 would therefore operate under extreme load and the high pressure piston 4 would merely idle. Furthermore, in order to take care of the large quantity of air displaced by the low pressure piston 3 under such a condition excessively large inlet and outlet valves would be required to avoid loading of said piston by a pressure far exceeding that in the reservoir 1.

To avoid these difficulties the reducing valve device 83 therefore functions to reduce the pressure of the air supplied from the chamber 55 to the inlet of the compressor during recompression to a degree such that when the air is discharged from the low pressure cylinder its pressure will be lower than in the reservoir 1 so as to thus cause the high pressure piston 4 to assume part of the load of recompression, even under the most extreme pressure condition obtained such as following equalization of the pressures in the reservoir 1 and chamber 55.

It has been found that by using the reducing valve device 83 and obtaining all the benefits thereof, that recompression of the air from chamber 55 back into the storage reservoir 1 is obtained in substantially the same time as without the reducing valve device. It has also been found that by recompressing the air from chamber 55, which may be under a relatively high degree of pressure, back into the storage reservoir 1 the pressure in said reservoir may be completely restored in only about twenty percent of the time required for a corresponding restoration with the intake of the compressor open to the atmosphere. Furthermore, restoration of the pressure in supply reservoir 1 by recompressing the air from chamber 55 provides a saving in power consumed as great as for instance forty percent, as compared to effecting such restoration by drawing air directly from the atmosphere at the inlet of the compressor.

The reducing valve device 83 will operate as above described to limit the pressure in chamber 82 and thus at the compressor intake as long as the pressure in chamber 55 of the oil reservoir is of a higher degree than in chambers 82 and 92. However, when the pressure in chamber 55 becomes reduced to a degree substantially equal to that in chambers 82 and 92, the spring 96 will deflect the diaphragm 94 upwardly and move the valve 89 to its fully open position shown.

With the valve 89 in its fully open position the compressor will continue to operate to recompress the air from the oil reservoir chamber 55 back into the air supply reservoir 1 until the pressure in said chamber acting on diaphragm 35 of the governor cutout device 21 is overbalanced by the opposing pressure of spring 30. This overbalancing will be obtained when the pressure of the air in the oil reservoir chamber 55 and intake pipe 13 becomes reduced to some low degree such

as two pounds and when such occurs the spring 30 will return the diaphragm 35 to its normal position shown to thereby close the valve 21 and open the valve 24 and thus cut the electric governor 20 into control by the pressure of the air in the supply reservoir 1.

If at this time the pressure in the reservoir 1 is at or above the cut-out adjustment of the electric governor 20 said governor will immediately 10 operate to stop the compressor 2 in which case the relatively low degree of air pressure still existing in chamber 55 above the oil in reservoir 40 will be bottled up. However in case the pressure in the reservoir 1 is not yet restored to the cutout 15 adjustment of the electric governor 20 the compressor will continue to operate to compress air into the tank 1 until such cutout pressure is obtained at which time the governor will operate to stop the compressor.

20 If the compressor 2 continues to operate after the cutout device 21 operates to connect the electric governor 20 up for control by the pressure of the air in the reservoir 1, this continued operation will cause a further reduction of pressure 25 in chamber 55 above the oil in reservoir 40, and this further reduction may reduce the pressure in said chamber to substantially atmospheric pressure. In case the reservoir 1 is not completely recharged at the time the pressure in 30 chamber 55 thus becomes reduced to atmospheric pressure the compressor 2 will continue to operate and draw air from the atmosphere through the air strainer 89 and past the check valve 85. It will thus be apparent that at the time the compressor 2 stops operating the pressure in chamber 55 above the oil in reservoir 40 may be of any 35 degree from substantially atmospheric pressure up to that existing at the time the cutout device 21 operates to connect the governor 20 up for control from the reservoir 1.

When the hoist is in its lowered or normal position it is intended that the reservoir 1 will be substantially filled with oil as shown in the drawing. Under this condition a relatively small amount of compressed air from the tank 1 will be required to displace the required amount of oil from the reservoir for raising the hoist to its elevated position.

If a less amount of oil is in the reservoir 1, as may be the case due to loss by leakage after long use, a greater amount of compressed air will be required from the air supply reservoir 1 to displace the required amount of oil from the oil reservoir to effect a desired hoisting operation.

Thus the amount of compressed air required from the reservoir 1 to effect a hoisting operation will vary according to the amount of oil in the reservoir 1. Where the amount of air required for effecting a hoisting operation is of a minimum and is drawn from the air supply reservoir when charged to the cutting-out point of the governor 20, reservoir 1 may not become reduced to the cutting-in point of the governor 20. In such a case the compressor 2 will not be caused to operate during the hoisting operation, but upon movement of the lever 42 back to its normal position will operate to merely recompress the air from chamber 55 back into the air supply reservoir 1 and thereby restore the pressure in said reservoir to substantially its original value.

Where, however, the amount of compressed air needed for effecting a hoisting operation causes a reduction in pressure in reservoir 1 to below

the cutting-in adjustment of the governor 20 or in case the pressure in reservoir 1 is of such a reduced degree as to cause the governor to cut-in, even in case of a completely filled oil reservoir, the compressor 2 may be caused to operate as above described to completely recharge the air supply reservoir 1 during a hoisting operation. In such a case the subsequent recompression of air from chamber 55 back into reservoir 1 will increase the pressure therein to some degree above the cutting-out adjustment of the governor 20. To avoid the pressure in the air supply reservoir 1 from becoming increased to an undesirably high degree under such a possible condition a safety valve 101 is connected by a pipe 102 to the reservoir and is so adjusted as to open and exhaust air from said reservoir when the pressure therein is increased to a certain maximum degree, which may be for instance fifteen pounds above the cutout adjustment of the electric governor 20. However, except under some extreme condition, such as in case of a small supply of oil in the oil reservoir 40 and the pressure obtained in the air supply reservoir 1 by recompression from chamber 55 may never attain the value required to operate the safety valve device 101.

When the operator desires to lower the hoist he turns the handle 42 in a clockwise direction to a lowering position at the right hand side of the normal position in which the handle is shown in the drawing. This operation of the handle to the lowering position actuates the lever 50 and thereby the plunger 49 to unseat the check valve 46 against the opposing pressure of the bias spring 47. With the air pressure in chamber 55 above the oil in reservoir 40 reduced to or near that of the atmosphere the weight of the elevated body will then cause flow of liquid back through the supply pipe 45 and past the unseated check valve 46 into the reservoir 40 and this flow will continue until the body has been returned from its elevated position to its normal lowered position at which time the handle 42 may, if desired, be returned from its lowering position to its normal position shown. The return of handle 42 to its normal position at this time is, however, of no consequence.

In case the handle 42 should be moved directly from its raising position to its lowering position, as might possibly be done under certain conditions, the oil from the hoist will flow back through the supply pipe 45 to the reservoir 40 only as the pressure of the compressed air in chamber 55 is reduced by operation of the compressor to recompress same back into the air supply reservoir 1. This recompression however occurs rapidly so as to quickly evacuate the chamber 55 of compressed air and thus will not materially retard the lowering of the elevated body.

As above mentioned, a certain low degree of air pressure may be bottled in chamber 55 above the oil in reservoir 40 at the time the compressor stops, this bottled pressure being determined by the pressure of spring 30 in the governor cutout device 21. The pressure of this spring need only be sufficient to insure that the valve 24 will be open when the pressure in the compressor intake pipe 13 is substantially that of the atmosphere, and may therefore be such as to require only a relatively low pressure such as two pounds in the intake pipe for seating the valve 24. The bottled pressure in chamber 55 under the condition above mentioned may,

therefore, be two pounds and this is permissible since normally a greater pressure is required to counteract the weight of the parts of hoisting mechanism connected to the oil supply pipe 45. 5 Thus, even with a bottled pressure of two pounds in chamber 55 above the oil in reservoir 40, a complete lowering of the hoist is normally ensured.

10 In the manually operative control valve device 41 the air release chamber 76 has a communication directly with the atmosphere which is normally closed by a hand-operated valve 103. This valve is provided for manually releasing the compressed air from chamber 55 to permit lowering 15 of an elevated body in case for any reason, some part of the apparatus which is normally operative to withdraw the air from said chamber automatically as above described, should fail, as for instance due to a failure of the supply of 20 electric current for operating the motor 10.

Summary

It will now be noted that the improved hoist 25 control mechanism provides for positive and selective raising and lowering operations regardless of the load being elevated and ensures that the load or body will not be dropped during a raising operation or while the load is in a raised condition, in case of failure of the compressed 30 air in the system.

The system provides for most economical operation by recompressing the once used compressed air from the oil reservoir back into the compressed air supply reservoir. It will be noted 35 that the compressed air which has been once used to effect a hoisting operation is never vented to the atmosphere unless due to some rare condition the recompression causes such an increase in pressure in the supply reservoir as to cause 40 opening of the safety valve device 101.

The reducing valve in the recompression connection to the intake of the compressor insures intended compound operation of a compound 45 compressor, avoids excessive loading of and possible damage to any part of the compressor and also prevents loss of oil from the crankcase of the compressor when the crankcase is connected to the compressor inlet and thus charged with compressed air.

50 The recompression system including the reducing valve device also provides for obtaining a quicker recharge of the air supply reservoir, and a saving of power consumed by motor 10 to maintain said reservoir in a sufficiently recharged condition for operating the system, as compared to a system not embodying the improved recompression feature.

It should also be noted that recompression of the air from chamber 55 in the oil reservoir is insured regardless of the air pressure which may be acting in the supply reservoir 1 at the time the operating handle 42 is moved out of its raising position, since the governor cutout device 21 will operate at this time to ensure operation of 65 the compressor 2.

In case the recompression system fails for any reason with a load in an elevated position, the relief valve 103 provides for lowering of the load as described.

70 Having now described my invention, what I claim as new and desire to secure by Letters Patent, is:

1. In combination, a first reservoir adapted to be charged with compressed air, an air compressor having its inlet connected to an inlet

pipe and having its discharge open to said reservoir and adapted to receive air from said inlet pipe and to compress same into said reservoir, a governor device for controlling said compressor and normally responsive to the pressure of air in said reservoir and operative upon an increase in such pressure to a desired degree to stop said compressor and upon a reduction in the pressure in said reservoir to a desired lower degree to start said compressor, said inlet pipe having a communication with the atmosphere; a check valve in said communication arranged to provide for flow of air from the atmosphere to said inlet pipe and adapted to be operated by pressure in said pipe to close said communication, a second reservoir adapted to be charged with compressed air at a pressure not exceeding that in said first reservoir, valve means operative to open communication between said second reservoir and said inlet pipe to provide for flow of compressed air from said second reservoir to the inlet of said compressor, and means controlled by the pressure in said inlet pipe and operative when the pressure therein is increased to a chosen degree above that of the atmosphere to effect operation of said governor device to cause said compressor to operate regardless of the pressure in said first reservoir.

2. In combination, a first reservoir adapted to be charged with compressed air, an air compressor adapted to charge said reservoir, an air inlet pipe for said compressor adapted to be opened to the atmosphere, a governor device for controlling the operation of said compressor and normally controlled by the pressure of air in said reservoir and operative upon an increase in such pressure to a chosen degree to stop said compressor and upon a reduction in such pressure to a chosen lower degree to start said compressor, cutout means controlling communication between said governor device and reservoir and normally establishing such communication to render said governor device responsive to the pressure of fluid in said reservoir and operative to close such communication to thereby render said governor device operative to effect operation of said compressor regardless of the pressure in said reservoir, means controlled by the pressure of fluid in said inlet pipe for controlling said cutout means and operative when the pressure in said inlet pipe is of a degree substantially no greater than that of the atmosphere to actuate said cutout means to effect opening of said communication and when of a greater degree to actuate said cutout means to effect closing of said communication, a second reservoir adapted to be charged with fluid at a pressure not exceeding that in said first reservoir, a valve operative to connect said second reservoir to said inlet pipe for supplying compressed air from said second reservoir to the inlet of said compressor, and a check valve operative upon the supply of compressed air from said second reservoir to said inlet pipe to close communication between said inlet pipe and atmosphere.

3. In combination, a first reservoir adapted to be charged with compressed air, an air compressor adapted to compress air into said reservoir, an air inlet pipe for said compressor, a compressor governor for controlling said compressor normally responsive to the pressure of air in said reservoir and operative to effect operation of said compressor when the pressure of the air in said reservoir is less than a chosen degree and

to stop operation of said compressor when the pressure of air in said reservoir is increased to a chosen higher degree, a second reservoir adapted to be charged with compressed air at a pressure not exceeding that in said first reservoir, valve means operative to connect said second reservoir to said inlet pipe to supply compressed air from said second reservoir to the inlet of said compressor, and means operative by the pressure of air supplied from said second reservoir to said inlet pipe to effect operation of said governor to cause said compressor to operate regardless of the pressure of fluid in said first reservoir, said means being operative when the pressure in said second reservoir is reduced by operation of said compressor to a chosen low degree to connect said governor to said first reservoir for control by the air pressure therein.

4. A hydropneumatic hoist control mechanism comprising a liquid reservoir containing a body of liquid and having above the liquid an air chamber to which compressed air is adapted to be supplied for displacing the liquid to effect a hoisting operation, a certain minimum pressure of compressed air being required in said chamber to initiate said hoisting operation, a compressed air supply reservoir, an air compressor adapted to compress air into said supply reservoir, an air intake pipe for said compressor, manual means operative to open communication between said supply reservoir and said chamber for supplying compressed air to act on said liquid for effecting a hoisting operation, said manual means being operative to close communication between said compressed air supply reservoir and said chamber and to connect said chamber to said inlet pipe for supplying compressed air from said chamber to the inlet of said compressor, a pressure governor normally responsive to the pressure in said air supply reservoir for maintaining the pressure therein between certain chosen limits, and means operative upon supply of compressed air from said chamber to said inlet pipe to effect operation of said governor to cause said compressor to operate to recompress the air from said chamber into said reservoir regardless of the pressure of fluid in said reservoir.

5. A hydropneumatic hoist control mechanism comprising a liquid reservoir containing a body of liquid and having above the liquid an air chamber to which compressed air is adapted to be supplied for displacing the liquid to effect a hoisting operation, a certain minimum pressure of compressed air being required in said chamber to initiate said hoisting operation, a compressed air supply reservoir, an air compressor adapted to compress air into said supply reservoir, an air intake pipe for said compressor, manual means operative to open communication between said supply reservoir and said chamber for supplying compressed air to act on said liquid for effecting a hoisting operation, said manual means being operative to close communication between said compressed air supply reservoir and said chamber and to connect said chamber to said inlet pipe for supplying compressed air from said chamber to the inlet of said compressor, a governor for controlling said compressor and normally subject through a passage to the pressure of compressed air in said supply reservoir and operative when such pressure exceeds a chosen degree to stop said compressor and when of a less degree to start said compressor, and means operative upon supply of compressed air

from said chamber to said inlet pipe to close communication between said passage and reservoir and to open said passage to the atmosphere so long as the pressure in said chamber is above said minimum degree and to reconnect said passage to said supply reservoir when the pressure in said chamber is less than said minimum degree, to thereby render said compressor operative to compress the compressed air from said chamber into said supply reservoir until the pressure in said chamber is reduced to said minimum pressure regardless of the degree of pressure acting in said supply reservoir.

6. A hoist control system comprising a hydraulic reservoir containing a body of liquid and having above the liquid body a chamber adapted to receive compressed air for displacing said liquid to effect a hoisting operation, an air supply reservoir, an air compressor operative to compress air into said reservoir, a governor controlled by the pressure of air in said reservoir for controlling the operation of said compressor and providing for the maintenance of the air pressure in said reservoir between chosen limits, manually operative valve means movable to a position for supplying air from said supply reservoir to said chamber to displace liquid therefrom and movable out of said position to close communication between said reservoir and chamber and to connect said chamber to the intake of said compressor, and means operative by the pressure of air supplied from said chamber to the intake of said compressor to effect operation of said compressor to recompress the air from said chamber back into said reservoir regardless of the degree of pressure in said reservoir.

7. A hydropneumatic hoist control system comprising a hydraulic reservoir containing a body of liquid adapted to be displaced by compressed air supplied to a chamber above the liquid to effect a hoisting operation, a compressed air supply reservoir, an air compressor for charging said air reservoir, a pressure governor arranged to be controlled by the pressure of air in said air supply reservoir for controlling the operation of said compressor and operative to regulate said compressor to maintain the pressure in said air reservoir between chosen limits, and manually operable means having one position for venting compressed air from said chamber and movable to another position for connecting said chamber with said air supply reservoir to thereby provide compressed air on said liquid to effect displacement thereof, said manually operable means comprising two valves, means connecting said valves for movement in unison, one of said valves constituting a supply valve controlling

communication between said air supply reservoir and said chamber and the other valve constituting an exhaust valve controlling communication between said chamber and an opening for releasing compressed air from said chamber, the said means connecting said valves providing for the closing of one valve upon opening of the other, a movable abutment connected with said valves and constantly subject on one face to the pressure of the compressed air in said supply reservoir and normally subject on the opposite face to the pressure of air from said supply reservoir, spring means acting on said valves for closing said supply valve and opening said exhaust valve when the opposite sides of said movable abutment are both subject to the pressure of air from said supply reservoir, pilot valve means controlling communication between said opposite side of said movable abutment and said supply reservoir and operative to close same and to vent the compressed air from said opposite side of said abutment for thereby rendering said abutment operative to open said supply valve and close said exhaust valve, a lever operative by manual pressure to effect operation of said pilot valve means to vent compressed air from said opposite side of said abutment means, and means operative upon release of manual pressure on said lever to actuate said pilot valve means to reconnect said opposite side of said abutment to said compressed air supply reservoir to thereby render said spring means effective to close said supply valve and to open said exhaust valve.

8. A hydropneumatic hoist control system comprising a hydraulic reservoir containing a body of liquid adapted to be displaced by compressed air supplied to a chamber above the liquid to effect the hoisting operation, an air supply reservoir, an air compressor operative to charge said reservoir with compressed air, manually controlled valve means having one position for supplying compressed air from said air supply reservoir to said chamber to effect displacement of liquid from said hydraulic reservoir, and another position for closing communication between said air supply reservoir and chamber and for connecting said chamber to a pipe connected to the inlet of said compressor, means operative upon supply of compressed air from said chamber to said pipe to effect operation of said compressor to recompress the air from said chamber back into said air supply reservoir, and means adapted to be operated manually to release compressed air from said chamber upon failure of said compressor to withdraw the compressed air from said chamber.
